BOTTLE

Montgomery Ferar, Huntington Woods, Mich., assignor to Hercules Powder Company, Wilmington, Del., a corporation of Delaware

Filed Oct. 20, 1964, Ser. No. 82,239

Term of patent 14 years

(Cl. D58—6)

FIG. 1

FIG. 3

FIG. 1 is a perspective view of a side and end of a bottle embodying my new design;

FIG. 2 is a top plan view thereof; and

FIG. 3 is a side elevational view thereof.

The end and side of the bottle not shown are substantially identical to the end and side shown in the accompanying drawing.

The characteristic features of my design reside in the particular configuration of the insert panel located on two opposing sides of the bottle.

I claim:

The ornamental design for a bottle, substantially as shown and described.
